US0D1048314S

(12) **United States Design Patent** (10) **Patent No.:** **US D1,048,314 S**
(45) **Date of Patent:** **** Oct. 22, 2024**

(54) **SPRAY GUN**

(71) Applicant: **NINGBO JIANGHUI ELECTRIC TECHNOLOGY CO., LTD**, Zhejiang (CN)

(72) Inventor: **Yinjiang Wang**, Zhejiang (CN)

(73) Assignee: **NINGBO JIANGHUI ELECTRIC TECHNOLOGY CO., LTD**, Ningbo (CN)

(**) Term: **15 Years**

(21) Appl. No.: **29/890,623**

(22) Filed: **Apr. 25, 2023**

(30) **Foreign Application Priority Data**

Mar. 29, 2023 (EM) 015016167-0001

(51) **LOC (14) Cl.** **23-01**

(52) **U.S. Cl.**

USPC **D23/225**

(57) **CLAIM**

The ornamental design for a spray gun, as shown and described.

DESCRIPTION

FIG. 1 is a perspective view of a spray gun showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 shown in FIG. 1; and,
FIG. 10 is an enlarged view of portion 10 shown in FIG. 2.
The dash-dash broken lines in the drawings depict portions of the spray gun that form no part of the claimed design. The dot-dash broken lines in the drawings represent the boundaries of enlarged portion that form no part of the claimed design.

1 Claim, 10 Drawing Sheets
